United States Patent Office

Des. 185,874
Patented Aug. 11, 1959

185,874

CEILING LIGHT FIXTURE OR SIMILAR ARTICLE

Harold W. Rambusch, Lloyd Harbor, and Joaquin Santos,
Garden City, N.Y., assignors to Rambusch Decorating
Company, New York, N.Y., a corporation of New York

Application June 30, 1958, Serial No. 51,595

Term of patent 14 years

(Cl. D48—23)

What is claimed is:

The ornamental design for a ceiling light fixture or similar article, as shown.
